UNITED STATES PATENT OFFICE.

SAMUEL W. DOUGLASS, OF NEW YORK, N. Y.

APPARATUS FOR THE FORMATION OF DEEP WELLS.

SPECIFICATION forming part of Letters Patent No. 339,630, dated April 13, 1886.

Application filed January 14, 1886. Serial No. 188,489. (No model.)

To all whom it may concern:

Be it known that I, SAMUEL W. DOUGLASS, of the city, county, and State of New York, have invented an Improvement in Apparatus 5 for the Formation of Deep Wells, of which the following is such full, clear, and exact description as will enable others skilled in the art to make and use the same, when taken in connection with the accompanying drawings, in 10 which—

Figure 1 is a perspective view showing connection through the lower supply conduit, casing, or tube in section. Fig. 2 is a perspective view showing connection through the 15 upper supply conduit, casing, or tube in section. Fig. 3 is a vertical section of the swivel-plunger. Fig. 4 is a vertical section of a three-way valve. Fig. 5 is a horizontal cross-section of the same. Fig. 6 shows a section of 20 the plunger in vertical section. Fig. 7 is a section of modification of three-way cock for plunger-rod. Fig. 8 is a section of modification for cock in supply-pipe.

This invention relates to the devices whereby 25 pipes or tubes may be sunk in sands or quick-sands, marls, clays, &c., by projecting therein a tube or pipe in sections, adding additional sections at the upper end, and maintaining in 30 the pipe a continuous flow of water, and is an improvement on the apparatus described in Letters Patent No. 277,695, to Jarvis B. Edson, and in Letters Patent to me, No. 290,546.

This my invention consists of the combination 35 of a swivel-plunger on a hollow stem passing through it, a three-way cock attached to said stem, and couplings for two water-supply conduits, with a water-supply and a three-way cock and two water-supply conduits, the whole 40 arranged so that the swivel-plunger may be fitted in a well tube or pipe and continuous water-supply maintained through the two conduits, so as to allow the addition of lengths of 45 pipe or tube at the upper end of the pipe being sunk, and the various combinations and methods of sinking wells hereinafter specified and claimed.

The plunger consists of a body, A, made of about the same diameter as the inside of the pipe P, (to be sunk,) in which it is to be used, 50 preferably somewhat smaller. Through the center of the body A is a hole or opening in which a pipe or hollow stem, B, is secured, so

that the plunger may revolve independently of the stem, as hereinafter described.

To the body of the plunger A are attached 55 the cup leather packings or buckets M and N, two or more in number, all cupped in the same direction, and all secured between proper rings or followers to the plunger-body A by the screws K K, or by any appropriate means, 60 as by screw-rings firmly attached to the body of the plunger. The cup-leathers make a tight joint and act as a packing between the tube or pipe P and the plunger to which they are attached when subjected to an upward 65 pressure of water, and conform themselves to the inequalities of the pipe, and allow the pipe P to be lowered over them without much friction. The cup-leathers can be placed any desired distance apart, and will when placed a 70 few inches apart cover the joint between two sections of pipe, and one of the cup-leathers will prevent leakage up past the plunger. The pipe or hollow stem B is made so that its lower end is smaller than the rest of the stem 75 up to the shoulder b, and has on its end a screw-thread, C. At the other end of the stem B is cut a screw-thread, C'. The smaller portion of the stem B is passed through the body of the plunger A until the shoulder b comes on 80 the body of the plunger or on washers or metal friction-collars W W W, when the extreme end projects below the plunger. On the projection is placed the washer or collar X, and fastened by the nut C, screwed on the thread 85 c, which nut is held in place by a set-screw or keeper, D. The stem B and plunger A are thus united, so that one may revolve freely without the other and maintain a water-tight joint between them, thus allowing the tube P 90 to be revolved without turning the stem B, and without wearing the packing between the plunger and the pipe P.

To the upper end of the stem B, on the screw-thread C', is fastened the three-way cock 95 E, through which water is supplied from either of two water-conduits, H' or J, made attachable and detachable at the openings in said cock. The cock is shown in Figs. 4, 5, and 6, and consists of the barrel E, having 100 three openings, G, G', and H, each provided with internal screw-threads, and the valve F, arranged therein, with an appropriate handle, so that the valve may be turned to close either

the opening G or H, leaving the other openings clear. The water-supply conduits H' and J are arranged to be attached by screw-threads to the openings H and G, respectively, and will 5 give a water-supply to the stem B through the valve from one or the other, as may be determined by the position of the valve F. The conduit not in use as a supply-pipe may be detached from the cock. The valve F is so 10 made that the greatest outside diameter is less than the inside diameter of the pipe P, in which the apparatus is to be used. The water-conduit H' is shown as a hose-connection with a short coupling-tube at the end, and the 15 water-conduit J as a long pipe, B', provided at the upper end with a swivel-connection, R, with a hose, H², to the water-supply. Any other appropriate connection may be substituted without departing from the nature of 20 this my invention, as a continuous hose from the cock E to the cock S as a system of jointed or hinged tubing.

The water-conduits H' and H² connect with a three-way cock, S, similar in construction to 25 that above described, through which water may be delivered to one or the other conduit, as desired, by turning the valve therein. It is apparent that where two water-supplies are used the three-way cock S may be omitted and 30 a simple cock placed in each supply.

Instead of the three-way cock E a check-valve may be placed at each of the openings G and H, as shown in Fig. 7, and the supply regulated by the valve S, in accordance with 35 the conduit through which water is to be supplied.

In Fig. 7 the barrel is made with three openings, like the barrel of cock E. There is, however, no valve F, and there are no openings 40 in the barrel for the valve F to pass through. In the opening G is placed the valve-seat and grating, in which the valve 10 fits and is guided by a valve-stem passing through the grating. This valve is held normally closed to the 45 valve-seat by a spring on the stem bearing on the grating and a pin in the valve-stem. In the opening H are placed a valve-seat and grating in which the valve 12 fits and is guided by a double valve-stem, one end passing 50 through the grating across the opening H and the other end through the bridge 9 on the side of the barrel opposite the opening H. This valve 12 is held normally to its seat by a spring on the stem bearing against the bridge 9 and 55 the valve, the water-pressure on either valve 10 or 12 at the openings G or H being sufficient to open one and to tend to further close the other and prevent leakage.

Instead of the three-way valve S a T-coupling and two valves may be substituted, as 60 shown in Fig. 8, wherein the conduit H' is connected with cock 14 and conduit H² with cock 16. These variances may be made without departing from my invention.

65 The apparatus above described is used in maintaining a continuous flow of water in a tube or pipe P while it is being sunk in sand

or other like ground without interrupting the flow, even when sections are added to the pipe P at its upper end, and is intended to be used 70 with such pipe P when it is armed, or provided at its lower end with a point, Y, through which are passages for the outflow of the water supplied to the tube P.

The mode of operation is as follows: On a 75 suitable derrick—such as are commonly used in well-boring, and are shown at Figs. 1 and 2—is raised one section of the pipe P, (shown at its lower end with a point, Y,) by suitable ropes attached to a clamp, L, which holds the 80 pipe P. Into the pipe P is introduced the plunger A, with its stem B attached, so that the cup of the cup-leathers M and N is downward and the extension of the stem is upward. The water-conduit H' is attached at 85 opening H and a water-supply made by turning the valves in the proper manner, which will cause a flow through the pipe P and the head Y. The stem B is held in a clamp, K, on the derrick, which clamp can be readily 90 opened and closed, and through which the stem may pass until the cock E reaches it. The flow of water out of the point Y washes away the ground and allows the pipe P to sink. When the top of that section of the 95 pipe P reaches a point low enough to permit another section to be added on top of it and below the top of the derrick, the stem B' is introduced in the sections, and they are raised on the derrick, and the stem B' is coupled into 100 the opening G of the three-way valve, and after making proper water-connections the valves are turned so as to make the supply 105 through the stem B', when the conduit H' is disconnected at H, and the second section of pipe P is coupled to the lower section, and as the pipe P sinks in the ground the plunger A, being held by the swivel-head to the derrick, the pipe P passes down about it until the top of pipe P is lower than the cock E, when the 110 clamp K' is fastened about stem B, (from which it was removed prior to fastening together the two sections of pipe P,) when the conduit H' is fastened to H and the valves changed, so as to make the water-supply through the conduit 115 H', when the stem B' is disconnected with cock E, and another section of pipe P is introduced, in the same manner as above, until sufficient depth of pipe is reached or an obstruction which prevents further sinking, in the 120 manner indicated.

What I claim as new, and desire to secure by Letters Patent, is—

1. In an apparatus for forming deep wells, the combination of a plunger with two detachable supply-conduits, and mechanism to close either inlet between the point of attachment of the conduits and the interior of the plunger, substantially as specified. 125

2. The plunger, in combination with a hollow stem, a three-way cock, and two detachable water-supply conduits, as specified and set forth. 130

3. The combination, with a tube or pipe, of

a plunger fitted within and having a hollow stem, a three-way cock, and two detachable water-conduits, as specified and set forth.

4. The combination of a plunger having a hollow stem connected with a three-way cock and two detachable water-supply conduits connected with a second three-way cock on the water-supply, as specified and set forth.

5. The combination of a tube or pipe with a plunger fitted within, in connection with a hollow stem, and a three-way cock, and two detachable water-supply conduits connected with a three-way cock on the water-supply, as specified and set forth.

6. The tube or pipe made in sections and a plunger fitted within one section, in combination with a hollow stem, a three-way cock, and two detachable water-supply conduits so arranged that additional sections of tube or pipe may be added at the upper end without interrupting a water-supply through the stem and plunger within the tube or pipe fed downward about the plunger, as specified and set forth.
